ELECTRICAL CONNECTOR HOUSING ASSEMBLY

John Philip Kunkle, Harrisburg, and Robert Charles Swengel, Jr., York, Pa., assignors to AMP Incorporated, Harrisburg, Pa.

Filed Jan. 27, 1969, Ser. No. 15,513

Term of patent 14 years

Int. Cl. D13—03

U.S. Cl. D26—1

FIG. 4

FIG. 3

FIG. 6

FIG. 5

FIG. 7

FIGURE 1 is an exploded perspective view of the electrical connector housing assembly;

FIGURE 2 is a perspective view similar to FIGURE 1 showing the parts in assembled condition;

FIGURE 3 is a top plan view of FIGURE 2;

FIGURE 4 is a side elevational view of FIGURE 3;

FIGURE 5 is a bottom plan view of FIGURE 2;

FIGURE 6 is an end view as seen looking from the top of FIGURE 3; and

FIGURE 7 is an end view as seen looking from the bottom of FIGURE 5.

We claim:

The ornamental design for an electrical connector housing assembly, substantially as shown.
